BOWLING GAME

Ronald Penn, Toronto, Ontario, Canada, assignor
of one-half to William Francis Joseph Hume,
Toronto, Ontario, Canada

Application December 13, 1933, Serial No. 702,104

2 Claims. (Cl. 273—51)

The invention relates to improvements in bowling games as described in the present specification and described in the accompanying drawing which forms part of the same.

- 5 The invention appertains in particular to a parlour game and has for its object the provision of a game of this nature in which a return runway extends beneath the playing board and has a guard at the head end to preclude the pins 10 from gravitating down it when knocked into the pit. A further distinctive feature resides in forwardly inclining the head or impact member so that it will direct the balls downwardly into the pit instead of onto the playing board.
- 15 A still further distinctive feature lies in the arrangement of the front or playing end of the board whereby a pocket is formed by prolonging the runway. This pocket retains the balls readily accessible to the player.
- 20 A general object of the invention is to produce a game structure in which the component parts are fitted together by means of grooves and secured by the tie-rods. This construction is not only economical to manufacture but also facilitates shipment in that it can be shipped knocked down instead of in its assembled form.

Referring to the accompanying drawing:

Figure 1 is a side elevation of the game.

Figure 2 is a longitudinal sectional view thereof.

Figure 3 is a plan view thereof.

Figure 4 is a vertical sectional view looking in the direction of the arrows and taken on the line 4—4 of Figure 2.

Figure 5 is a head end view.

Like numerals of reference indicate corresponding parts in each of the figures throughout the drawing of the invention.

40 In the drawing, the reference numeral 6 denotes the playing board which presents an elongated playing surface common to games of this nature. The head end 7 has the usual arrangement of five pins denoted at 8 at which the balls 9 are propelled by a cue in the hands of the player. An indent seat is preferably furnished, as customary, in the playing end 11 of the board to lodge a ball that is about to be played.

The playing board is fitted in grooves 12, 12 in the opposing side members 13. The side members have their head ends 14 increased in depth so as to extend well above the playing surface of the board, which terminates short of said head ends as seen from the drawing.

55 The head piece 15 or impact element is fitted in grooves 16 in the side members and is forwardly inclined in spaced relation to the end 7 of the playing board. The inclination of the head causes the balls striking it to rebound 60 downwardly.

Coextensive with the playing board and spaced from the underside thereof on a slight downward angle from the headpiece 15 is a runway member 17 fitted in the side members by means of grooves 18 and prolonged beyond the playing end 11 of said board. The member 17 composes a runway subjacent the playing board for the return by gravity of the balls. By prolonging the member 17 as at 19 and furnishing it with a cross-piece 20, a pocket 21 is formed in which the balls come to rest and can be conveniently picked out by the player.

The portion of the runway member 17 that lies between the playing board and the headpiece 15 forms the bottom of the pit 22 into which both the balls and the pins drop. In order to only allow the balls to gravitate down the runway a guard 23 is provided and has spaced fingers 26 between which the balls pass. The pins, however, on account of their size are retained in the pit.

The component parts of the game are secured in the groove connections by means of tie-rods 24 having nuts 25 tightened on their threaded ends. This forms a sturdy and easily assembled apparatus.

What I claim is:—

1. In a bowling game, a substantially horizontal playing board having a head end, pins disposed upon the head end thereof, balls for projection along the playing board and at the pins, elements forming a pit at the head of the board, said elements including a bottom member continued beneath the playing board and on a slight angle to form a gravity runway for the balls, and an apertured guard interposed at the entrance to the runway to retain the pins in the pit, said guard providing spaced vertical elements located a slightly greater distance apart than the diameter of the balls.

40

2. A bowling game composed of a playing board, opposing side members having grooves in which said board is fitted, said side members having their head ends continued beyond the board and increased in depth, the side members also having the opposite ends continued beyond the playing end of the board, a headpiece forwardly inclined and fitted in grooves in the said side members in spaced relation to the board, a bottom member extending from the headpiece on a slight downward angle beneath the playing board to form a runway, said runway extending beyond the playing end of the playing board and fitted in grooves in said side pieces, a cross piece rising from the lower end of the runway, tie rods extending from one to the other of the side members, and nuts on the tie rods to secure the component parts together.
